CALCULATING MACHINE

Robert L. Muller, Detroit, Mich., assignor to Burroughs Adding Machine Company, Detroit, Mich., a corporation of Michigan

Application October 19, 1933, Serial No. 694,230

9 Claims. (Cl. 235—60)

This invention relates to calculating machines, more particularly to a multiple register machine and concerns the register controlling mechanism therefor.

5 The present demand is for calculating machines capable of simultaneously performing a plurality of calculating operations. This requirement necessitates either a multiplicity of registers or suitable controls for two or more registers whereby 10 amounts may be entered simultaneously into the registers independently of each other and regardless of the character of the entry, and means for totaling the registers regardless of the condition 15 of the registers and character of the totals.

15 In posting bank account transactions, for example, it is desirable to enter the deposits or addition amounts in one column, the withdrawal or subtraction amounts in another column, and the daily balances mixed or otherwise in a third 20 column. For speed and efficiency, it is also desirable to be able to post a plurality of accounts simultaneously but independently at each cycle of operation of the machine.

25 To accomplish this desired end, it has been proposed in the past to divide the keyboard of a calculating machine, its actuator racks, and register into two sections so that in effect two registers are provided, each controlled by one section of the keys of the keyboard. This construction and arrangement made it possible to simultaneously enter two amounts, one in each of the register sections and if the register sections were each constructed for addition and subtraction, either type of entry could be made.

30 In such a machine totals could be taken at any desired time in either of the register sections provided that both register sections were in the same condition, that is, provided both were positive or both negative. If the balance was mixed, that is, if one section was in positive condition and the other in negative condition, one total only could be taken because the two register sections were not independent. It is obvious that such 35 a machine has certain limitations in that mixed balances cannot be taken if desired. Therefore, the machine cannot be used to print both positive and true negative totals.

It is, therefore, within the contemplation of 50 this invention to increase the flexibility of the machine by increasing the possible uses with a limited number of registers thereby having the effect of increasing the number of registers without, however, any consequent complicity of register control.

The general object of this invention is to provide an improved register controlling mechanism for a multiple register machine.

A more particular object is to provide an improved register controlling mechanism for multiple register calculating machines which will permit the simultaneous entry of amounts in the several registers and the taking of totals therefrom regardless of the condition of the register, that is, whether it contains a positive or negative 10 total.

Other objects and advantages of the invention will appear from the specification and drawings which illustrate one embodiment of the invention and in which,

15 Figure 1 is a left side sectional elevation of a calculating machine embodying the present invention with parts removed, the register controls being in normal position;

20 Fig. 2 is a perspective view from the front left corner of the machine showing the register control devices and associated mechanism for each register or section of registers with both sections in normal or positive condition;

25 Fig. 3 is an enlarged view of the center portion of Fig. 2;

30 Fig. 4 is a partial left side elevation taken in different planes showing the register controls in position after a negative balance has occurred in one section of the machine and the carriage having moved to the balance column and with the total key locked against depression as a warning to the operator of the machine;

35 Fig. 5 is also a partial left side elevation showing the register controls, and total key in position after a negative balance has occurred in one section and after the total key lock has been removed by manual operation and with the total key depressed for the first totaling operation of the mixed balance posting;

40 Fig. 6 is a fragmentary detail of the register control mechanism on the right side of the machine; and

45 Fig. 7 is a sample form in which two different mixed balance postings are illustrated.

The illustrated embodiment of this invention for accomplishing the heretofore-mentioned desired end is shown as applied to a "Burroughs" bookkeeping or posting machine such as that shown and described in the patent issued to Pasinski No. 1,778,506, although it will be obvious to those skilled in the art that the invention may be applied equally well to other types of calculating machines.

Calculating machine generally

As previously stated, the machine is a typical Burroughs bookkeeping or posting machine having a keyboard with depressible keys 1 which engage cranks 2 to which control wires 3 are attached which latter wires under the control of the keys limit the movement of actuator racks 4 and 4^a carried upon the forward ends of levers 6, pivoted at 7. Levers 6 carry type bars 8 upon their rear ends which are struck by hammers 9. The actuator racks 4 and 4^a engage add and subtract registers of the tumbling type comprising adding wheels 10 and 10^a and cooperating subtracting wheels 11 and 11^a carried by a supporting frame 12. The registers may be placed in either addition or subtraction position by a manually operable lever 13 which causes the register to be tumbled into either add or subtract condition in the usual manner. The illustrated machine being of the duplex type it also has a third register 14 (Fig. 1).

The keys, racks, printing mechanisms, and registers are divided into sections, two sections only being shown in this machine for the purpose of simplicity although it is obvious that more sections may be employed. This division makes it possible to simultaneously enter independent amounts in each section by depressing suitable keys in each section of the keyboard. The register sections are designated 10 and 10^a for the addition wheels and 11 and 11^a for the subtraction wheels (Fig. 2), wheels 10 and 11 being for the left section of the register and wheels 10^a and 11^a being for the right section of the register.

Since the entire register is carried and operated in a single frame 12, when one section of the machine is in condition for addition, the adjoining section of the machine is likewise in condition for addition, the same relation being true when the register frame is changed to subtract position. However, the amounts set up on the keyboard in each section are independently controlled by the keys of each section and accordingly the amounts contained in the separate sections may vary to any desired degree even to the extent of causing an overdraft or negative balance in one section and a positive balance in the adjoining section, or what is known as a mixed balance.

The machine is provided with the usual paper carriage 20 which supports a platen 21 and is slideable horizontally and may be tabulated into various columns. Furthermore, the carriage is provided with the well-known mechanism for automatically conditioning the machine for either addition or subtraction in selected columnar positions. For example, the machine illustrated is adjusted to condition the machine for addition in column 1, subtraction in column 2, and totaling in column 3, the balances in the latter column being either positive or negative amounts depending upon the condition of the registers. Each column is of sufficient width to permit two entries therein. Accordingly, it will be noted (Fig. 7) that each column contains two columns of figures for two different accounts or series of items. Entries in the two accounts may be entered simultaneously but independently except in the balance column as will be explained later.

The operation of the machine thus far described is as follows: After the proper amount keys 1 are depressed in one or more sections of the keyboard to actuate wires 3 to limit movement of the actuator racks, the machine is given a stroke of operation by oscillating shaft 22 (Fig. 1) either by a

hand crank or by means of a motor (not shown). During the forward stroke of the machine, the registers are disengaged from the racks 4 and 4^a, which racks are allowed to descend until limited against the index wires 3, which have been set by depression of the keys. After the racks have descended to their limits, hammers 9 drive type bars 8 against the platen 21 to print the amount on the paper forms carried by the paper carriage. During the return stroke of the machine, the registers are engaged with the actuator racks 4 and 4^a and during return of the racks to normal position the register wheels are rotated by the racks.

Assuming that the machine is in normal condition for addition, the addition wheels 10 and 10^a are engaged with racks 4 and 4^a and are rotated clockwise as viewed in Fig. 1 upon return of the actuator racks 4 and 4^a. The subtraction wheels 11 and 11^a being in engagement with the addition wheels 10 and 10^a, are, of course, rotated counterclockwise. If the machine is set in condition for subtraction by operation of lever 13, the subtract wheels 11 and 11^a will be engaged with the actuator racks 4 and will be rotated clockwise thus rotating the addition wheels 10 and 10^a in a counterclockwise direction during the return of the racks to normal position.

When a carry or transfer occurs during the adding or subtracting operation, the usual cam 24 or 24^a on either the add or subtract wheels 10, 11, 10^a or 11^a advances the wheel of the next higher order at the completion of the machine operation.

The usual total key T is provided and when depressed conditions the controls to engage registers with the racks during the forward stroke of the machine. No keys having been depressed, the racks are limited by the register pinions upon reaching zero instead of being limited by the index wires 3 which are not actuated.

If a smaller amount has been subtracted from a larger amount in one section of the register, the balance is positive and is taken from the addition register wheels 10. On the other hand, if a larger amount is subtracted from a smaller amount, in a given register, the balance is negative and the register must be tumbled until the subtraction wheels 11 are engaged with the actuator racks 4 after which a total is taken by zeroizing the subtract wheels 11. In the illustrated machine, there is no indication of which register is in negative condition, however, means are provided for locking the total key whenever either or both of the registers is in negative condition.

Negative total locks

Each section of the machine is provided with a negative total lock which mechanisms are indicated generally at A and B (Fig. 2), A indicating the negative total locking mechanism for the left section of the machine, and B for the right section of the machine. These mechanisms are substantially the same and will be described first in connection with the left section of the machine and then the slight distinctions pointed out between the two sections A and B. The negative total locking mechanism for the left section includes a lever 25 pivoted at 26 and terminating in a foot 27 in position to be engaged by cam 24 of the highest order of the addition wheels 10 (Fig. 2) and a second lever 28 pivoted at 29 and terminating in a foot 31 in position to be engaged by cam 24 of the highest order of the

subtract pinions 11. The upper end of lever 28 is in position to engage a stud 32 carried by one arm of a three-armed lever 33 pivoted at 34, the second arm of which terminates in a spear point 36 engageable with a detent 37. Normally when the machine is in positive condition the spear point 36 lies to the rear of detent 37 (Figs. 1 and 2) whereas, when the negative total mechanism has been actuated, spear point 36 lies forward of 10 detent 37 (Figs. 4 and 6) because of the counter-clockwise position assumed by lever 33 in Fig. 4, and clockwise in Fig. 6.

When the register goes negative, however, as when an overdraft occurs, cam 24 of the highest order of the subtraction pinion 11 engages the foot 31 and swings lever 28 clockwise about its pivot causing the upper end of lever 28 to move stud 32 and rotate three-armed lever 33 counter-clockwise, in Fig. 4, and clockwise in Fig. 6, thus 20 moving stud 38 carried by the upper end of the third arm of lever 33 out of the forward notch 39 of link 41 as shown in Fig. 4, raising link 41 slightly. The upper edge of link 41 underlies and engages a stud 42 carried by one arm of a bail 25 43 pivoted on the cross shaft 44 extending across the machine. Adjacent the left end, bail 43 is provided with a downwardly depending arm 46 which is yieldingly connected by spring 47 at its lower end to a pendant 48 (Fig. 4). When the 30 negative total lock is operative, pendant 48 engages a stud 49 carried by a forwardly extending arm 51 of a lever 52 urged clockwise by a spring 55 which also has an upwardly extending arm 53 underlying a stud 54 carried by the total key. 35 Accordingly when a negative total occurs in the left register section, the cam 24 will engage lever 28 and through the mechanism just described cause lever 52 to be rocked counterclockwise to present its arm 53 immediately below stud 54 to prevent depression of the total key, thus notifying the operator that a negative total occurs in one of the registers. The negative total lock mechanism thus far described is similar to that 40 illustrated and described in the previously mentioned Pasinski patent to which reference is 45 made for further details.

The negative total lock mechanism for the right section is similar to that for the left section shaft 44, being divided into two coaxial sections 44 and 44^a (Fig. 2). The bail 43^a for the right section corresponding to 43 for the left hand section extends to the left end of shaft 44 where it terminates in a depending arm 46^a yieldingly connected by a spring 47^a to a pendant 55 48^a, the pendant 48^a being engageable with stud 49 which projects from both sides of the extension 51 of the arm 52 as shown in Fig. 2. Because of the foregoing mechanism the total key will be locked when either register is in negative 60 condition or when either section contains a total contrary in sign to the current position of the add subtract lever. The operator, therefore, knows that one or both of the registers are in negative condition and the total key must be released before a totaling operation can be performed. If both register sections are in positive 65 condition, and frame 12 is in add position the negative total locks are, of course, inoperative and a total of both registers may be taken simultaneously and immediately. The same is true if both 70 sections and the frame 12 are in negative position provided the total keys are first released.

Negative total lock release

75 If either one or both of the register sections

is in negative condition, the total key is blocked against depression and must be released prior to taking a total. A manually operable lever 60 is provided for releasing the negative total block. The lever 60 is pivoted freely on shaft 44 and is 5 formed with a depending arm 61 (Fig. 4) engageable with both pendants 48 and 48^a to rock them away from the stud 49 to return lever 52 to non-locking position, i. e., to disable or normalize 10 blocking lever 52 after which the total key may 15 be depressed for taking the first of the totaling operations. Springs 47 and 47^a provide a yielding connection between arm 46 and pendant 48 and between arm 46^a and pendant 48^a, respectively, and permit movement of lever 60 although bails 43 and/or 43^a are held in clockwise and overdraft position by the negative total lock mechanism, i. e., the yielding connections permit movement of pendant 48^a although arm 46^a may be 20 blocked and vice versa.

In the machine which has been chosen for illustrating one example of a practical embodiment of the invention, the register frame is not moved from its adding position to its subtracting position and vice versa directly upon the movement 25 of the add subtract lever 13 from one position to the other but the register frame 12 is moved from the adding position to the subtracting position and reversely during and by the operation of the machine following a change in the position of 30 the lever 13. The machine is provided with a locking means (not illustrated) constructed as shown in the previously mentioned Pasinski patent, for locking the total key against depression for a total taking operation, in which the register must be engaged with the actuator racks during the forward stroke of operation, when the register frame is not in the position corresponding to the setting of the add subtract lever and must therefore be moved from the one to the other 35 position during the operation of the machine. That is, whenever the position of the add subtract lever and the position of the register frame do not agree depression of the total lever is prevented. To release the total key if it is blocked 40 by this locking means after the add subtract lever has been shifted to a position corresponding to the kind of total to be taken it is necessary to give the machine a spacing operation by which the register frame is moved to the position 45 corresponding to the new position of the add subtract means.

Mixed balance posting

The mechanism thus far described is not sufficient for taking totals when a mixed balance 55 is in the machine, that is when one section of the register contains a positive total and the other section contains a negative total. In order to take such totals provision must be made for 60 clearing or zeroizing the register or sections having totals of one sign during the first totaling operation while preventing the other section or sections, if the register has more than two sections, from zeroizing. In other words provision 65 must be made for independently taking a total from one section without affecting the other section and then taking a total of the remaining section or sections without affecting the first section which has been cleared because of the first 70 totaling operation.

Accordingly this invention provides means for first, totaling and zeroizing one or more sections independently of the other section or sections, i. e., while preventing clearing of the other sec- 75

tion and second, for enforcing manual operation of the control lever to subtract position if one register section is in overdraft condition to take the true negative total of such section while maintaining the other register section cleared. In order that a true negative total may be drawn from either section of the register, each section of the register is preferably provided with a "fugitive 1" mechanism, which is not illustrated but which is of a known type, such, for example, as that discussed in the Pasinski Patent No. 1,738,506 and as described and illustrated in detail in the Rinsche Patent No. 1,172,484. In the construction according to the Rinsche patent, the tumbling of the register from adding position to subtracting position, or vice versa, trips the tens transfer pawl (413^c of Rinsche) for the units order actuator rack (610 of Rinsche). If the register is tumbled from adding position to subtracting position, "1" is subtracted in the units order of the register, but if the register is tumbled from subtracting position to adding position, "1" is added in the units order of the register, as is well understood by those skilled in the art. In the machine of the present application the register and printing mechanism is split, as is capable of being done in Pasinski Patent No. 1,778,506, and, furthermore, the tens transfer pawls for the actuator racks, for the units orders of both sections of the register or all sections of the register, in case there are more than two sections, are tripped by the tumbling of the register from its adding to its subtracting position, or reversely in the same way, as the transfer pawl for the units order rack of the machine of the Rinsche patent is tripped. The mechanism which makes it possible to take mixed balances will now be described.

A plurality of hooks 70 and 70^a (Fig. 2) are secured to shafts 44 and 44^a, respectively, there being a hook for each actuator rack of each section of the machine, the hooks being proportioned to engage the actuator racks at predetermined times in total taking operations to prevent total taking in the associated registers.

The two sections of hooks 70 and 70^a are controlled independently of each other through the two negative total lock mechanisms in such a manner that when a mixed balance is carried as, for example, when an overdraft occurs in the left section of the machine and a positive total in the right section, the right section is allowed to zeroize while the left section is blocked and vice versa. In the event that an overdraft occurs in both sections of the machine and the operator is unaware of this condition the hooks 70 and 70^a of both sections engage their respective racks. Therefore during the first totaling operation in which operation the add subtract lever 13 and the register frame 12 will be in addition position no printing or zeroizing will occur, but during the second totaling operation in which the add subtract lever 13 and the register frame 12 will be in subtraction position, both sets of hooks will be released simultaneously and both sections will print true negative totals.

Considering first an overdraft in the left section of the machine. It will be recalled that under such condition the three arm lever 33 is moved counterclockwise. This lever carries a stud 71 which is moved rearwardly with the lever 33 and upon clockwise movement thereof (Fig. 6) engages a cam 72 formed on a lever 73 pivoted about stud 26 (Figs. 2 and 6). Lever 73 is normally urged counterclockwise as viewed in Fig.

2 and clockwise in Fig. 6 by a spring 74, but when an overdraft occurs it is moved by the stud 71 against the action of spring 74. Lever 73 carries a stud 76 upon its outer or forward end in position to engage under the forward end of a link 77 having an L-shaped slot at its forward end with a horizontal portion 78 and a vertical portion 79. For the right section of the machine similar parts are provided and designated by the same numerals but with the suffix ^a. The rear ends of links 77 77^a are pivotally connected to arms 81 and 81^a secured to a shaft 82 supported in the machine side frames extending across the machine parallel to shaft 44. Secured to shaft 44 is a depending arm 83, the lower end of which carries a square stud 84 which projects into the L-shaped slot 78, 79. A similar arm 83^a is secured to the shaft section 44^a and has a square stud 84^a projecting into the L-shaped slot in the link 77^a. When the machine is in normal position hooks 70 are held in disengaged position by springs 87, which tend to rotate shaft 44 counterclockwise (Fig. 2) until the upper end of arm 83 engages the front edge of the keyboard plate 88, and stud 84 lies directly under the vertical portion 79 of the L-shaped slot.

Shaft 82 is actuated by the total key through an arm 91 connected by a link 92 to the downwardly extending arm 93 of the total key lever T (Fig. 2). Upon depression of the total key, shaft 82 is rocked counterclockwise and links 77 and 77^a are moved rearwardly. If the left section of the machine is in positive condition stud 76 will hold link 77 in upper position where square stud 84 lies within the horizontal portion 78 of the L-shaped slot. Accordingly when the total key is depressed, link 77 is moved rearward but is moved idly on stud 84 and does not rock shaft 44 to move hooks 70 which therefore remain in normal or inoperative position so that the racks 4 are free for movement and total taking.

At this time, however, if the right section is in negative total condition the pin 76^a will be lowered by the negative total lock mechanism and permit link 77^a to drop to place stud 84^a in the vertical section 79^a of the L-shaped slot. Depression of the total key therefore will rotate shaft 44^a through link 77^a and arm 83^a to bring hooks 70^a into engagement with the racks of the right section to block those racks during the total taking operation for the left section of the register which has been assumed to be in positive condition. Of course if the condition of the two register sections were reversed the operations would be reversed and upon depression of the total key and a stroke of operation of the machine the racks in the left section would be prevented from dropping during taking of the total in the right section. If, on the other hand, both register sections were in negative condition while the add subtract lever 13 and the register frame 12 were in addition position, both hooks 70 and 70^a would be rocked to effective position and neither set of racks would be permitted to move upon release and depression of total key T during the operation of the machine.

Assuming again that the left section was in positive condition and the right section in negative condition, after the positive section of the machine has been cleared during the first totaling operation at which time actuator racks of the right section were held locked to prevent the right section from being zeroized, the negative total lock mechanism for the negative section of the machine will still be in negative position.

That is link 77^a will be in lowered position and must be moved to inactive position otherwise the hooks would remain engaged to block movement of the actuator racks of the right section during the second totaling operation, exactly as they were during the first totaling operation. Provision must be made therefore to normalize or disable link 77^a during the second totaling operation. The mechanism for this is as follows:

- 10 Referring to Fig. 2 it will be seen that subtraction control lever 13 is pivoted at 95 to the machine frame and carries a stud 96 which engages a forked end of a lever 97 secured to a shaft 98 supported by brackets carried by the machine side frames. Shaft 98 carries two arms 99 positioned to engage studs 101 carried by levers 102 journaled upon shaft 82. Levers 102 extend forwardly and carry at their ends laterally projecting studs 103 which underlie links 77 and 77^a.
 15 When arms 102 are rocked by movement of the subtraction control lever 13 from addition to subtraction position, studs 103 engage links 77 and 77^a and raise them sufficiently to bring the horizontal portions 78 and 78^a of the L-shaped slots in operative position relatively to the studs 84 and 84^a. Therefore, during the second total taking operation, which is a negative total taking operation in the present example, (Fig. 7), the hooks 70^a of the right hand section will be free of the racks 4^a of that section, and because the right hand register section pinions are in negative condition, a total taken from that section will be a true negative total. If the operator realizes that both sections of the machine are in negative condition he may immediately shift subtraction control lever 13 to subtract position and simultaneously take a true negative total of both sections of the register in one machine operation without first going through an idle positive totaling operation. The negative totals as well as the subtract items may be printed in red as is the customary practice to distinguish from positive totals and negative totals.

Operation

45 The operation of the machine will be summarized in connection with Fig. 7 which illustrates one form of record sheet or work sheet which may be used in connection with a machine embodying the principles of the foregoing invention. In this form the sheet is divided into three columns, column 1 for amounts that are to be added, column 2 for amounts that are to be subtracted and column 3 for the totals whether they be positive 50 or negative. Each column is of sufficient width to take two independent entries and the machine is arranged so that it automatically is put in subtraction condition when the form reaches column 55 2. It will be understood that additional columns 60 may be provided for other addition or subtraction entries if desired, a simple form being shown for convenience.

In the illustrated example, the necessary keys of the two divisions of the keyboard are depressed 65 to enter 555 articles in the left division and 5.55 in the right section of the register while the paper carriage is in column 1. The machine is then given a stroke or cycle of operation after which the paper carriage is automatically tabulated to 70 column 2. While the paper carriage is in column 2 position the proper keys are depressed in the two divisions of the keyboard to subtract 222 from 75 555 posted in the left register section and 7.77 from 5.55 posted in the right register section, after which the machine is given a stroke of oper-

ation and the paper carriage is automatically tabulated to column 3. The total in the left register section is a positive amount but inasmuch as a larger amount was subtracted from a relatively smaller amount in the right register section the 5 right register section is in negative condition thus resulting in a mixed balance, that is, a positive total, or balance, in the left section; and a negative total or balance in the right hand section. This condition will be indicated because 10 the total in the registers being negative the total key will be locked against depression because of pawl 24^a on the subtract pinion 11^a of the highest order engaging arm 31^a and setting into motion the necessary mechanism as previously described to cause lever 52 to be rocked counterclockwise to bring its upper arm 53 immediately beneath stud 54.

The operator then takes two spacing strokes 2 to tumble the registers to add condition if not 2 already there and to restore the racks to normal position. He then releases the total key by manual operation of lever 60 which enables lever 52 to move clockwise to inoperative position by its 25 spring 55. The total key is then depressed and the machine is given a stroke of operation. During this stroke of operation the positive total 333 is taken on the register which is in positive condition, that is, the left register section, the right 30 register section is and remains locked against clearing or zeroizing by means of hooks 70^a which have been rocked into engagement with the racks 4^a by the mechanism set into motion by the negative total lock. This permits independent totaling of each of the two register sections without 35 affecting the other register section.

In order to take a total from the right register section which is in negative condition, it is necessary to move the subtraction control lever 13 to subtract position and give the machine two spacing strokes. Movement of lever 13 to subtraction 40 position disables hooks 70^a of the right section racks after which the total key is depressed with the subtraction control lever 13 in subtract position and the machine is given a stroke of operation 45 to take a true negative total 2.22 in the right register section. During this operation the left register section is retained in its zero position.

It follows from the foregoing that although 50 the different register sections are all carried in a single frame and are all simultaneously engaged with the actuator racks in positive or negative total taking relation the machine is capable of taking a mixed balance regardless of which register 55 contains a positive total and which one a negative total. In other words, it is possible to accumulate two or more groups or listings simultaneously until the balance column is reached, after which a positive total can be taken from one 60 section of the machine and a negative total can be taken from the other section of the machine, because of the automatic control of the racks depending upon the positive or negative condition of the register sections.

It will be apparent to those skilled in the 65 art that minor changes may be made in the details of construction without departing from the spirit and scope of the invention as defined in the appended claims.

I claim:

1. In a calculating machine having a register divided into a plurality of sections, each capable of addition and subtraction, differential mechanism for entering amounts in said registers, a plurality of depressible keys for controlling the 75

- entry of amounts in said register sections upon a single cycle of operation of said machine, total taking control means, locking devices controlled by the register sections in negative condition and 5 arranged to disable certain elements of said machine to prevent totaling of all register sections in negative condition, but being ineffective as to those register sections in positive condition, and means for preventing disabling by said locking 10 devices thereby enabling the taking of true negative totals from said register sections in negative condition after said register sections in positive condition have been totaled.
2. In a calculating machine having a register 15 divided into a plurality of sections each capable of addition and subtraction, differential mechanisms for entering amounts in said register, keys for controlling simultaneous entry of amounts in said register sections upon a single cycle of operation 20 of said machine, a single total key, connections therefrom for causing a total to be taken from each of said register sections, locking devices controlled in accordance with the condition of said register sections and arranged to disable certain 25 parts of said machine to prevent clearing of the register sections in predetermined condition during a total taking operation, and means for preventing disabling by said locking devices to enable the taking of a total from said latter register 30 sections after said register sections not in predetermined condition have been totaled.
3. In a calculating machine having a register divided into a plurality of sections each capable of addition and subtraction, differential mechanisms for entering amounts in said register, keys for controlling entry of amounts in said register sections upon operation of said machine, a total key, connections therefrom for causing a total to be taken from each of said register sections, locking 35 devices controlled in accordance with the condition of said register sections and arranged to disable certain parts of said differential mechanisms to prevent clearing of the register sections in predetermined condition during a total taking 40 operation, and means for preventing disabling by said locking devices to enable the taking of a total from said latter register sections after said register sections not in predetermined condition have been totaled.
4. In a calculating machine having a register 45 divided into a plurality of sections each capable of addition and subtraction, a plurality of depressible keys, differential movable racks controlled by said keys for simultaneously entering amounts in said register sections upon a single cycle of operation of said machine, total taking control means, locking devices controlled in accordance with the condition of said register sections and arranged to block movement of certain of said 50 racks during a totaling operation, but being ineffective as to other racks, and means for releasing said locking devices to enable the taking of totals from the register sections associated with said blocked racks after the register sections associated with other racks have been totaled.
5. A calculating machine adapted to be given 55 cycles of operation, having an amount determining differential mechanism including movable actuator racks normally restrained from movement, a registering mechanism capable of addition and subtraction whereby it may reach either a positive or a negative condition, said amount determining differential mechanism and said registering mechanism being divided into two sections operable independently of one another in 60 the entering and accumulation of amounts whereby one section of said registering mechanism may reach a negative condition while the other is in positive condition, total taking control means for causing a total to be taken from said registering mechanism, said total taking control means operating to cause an engagement between both of said sections and said racks for a total taking operation and to normally release all of said racks, means operated by an element 65 of said total taking control means when there is a negative total in one section of said registering mechanism to block the racks corresponding to said section during a total taking operation whereby when a positive total is taken from the section that is positive the negative section is undisturbed, and means for releasing the blocked racks whereby a negative total may be subsequently taken from the section that is negative.
6. A calculating machine adapted to be given 70 cycles of operation, having an amount determining differential mechanism including movable actuator racks normally restrained from movement, a registering mechanism, means for causing an engagement between said registering mechanism and racks in one relation for addition and the taking of positive totals and in another relation for subtraction and the taking of true negative totals, said amount determining differential mechanism and said registering mechanism being divided into two sections operable independently of one another in the entering and accumulation of amounts whereby one section of said registering mechanism may reach a negative condition while the other is in positive condition, total taking control means for causing a total to be taken from said registering mechanism, said total taking control means operating to cause an engagement between both of said sections and said racks for a total taking operation and to normally release all of said racks, means 75 operating automatically when there is a negative total in one section to lock said total taking control means, means controlled by said automatically operating means and actuated by said total taking control means to block the racks in the section that is negative during a total taking operation, means for releasing said total taking control means without releasing said blocked racks whereby a total may be taken from the section that is positive, and means for then releasing said blocked racks and conditioning said machine for a subtraction type of engagement between said registering mechanism and racks whereby a true negative total may be taken from the section that is negative.
7. In a calculating machine having a register divided into a plurality of sections each capable of addition and subtraction, depressible keys, differential mechanism controlled by said keys for simultaneously entering amounts in said register sections upon a single cycle of operation of said machine, a subtract lever for conditioning elements of the machine to cause it to perform subtraction, total taking control means, locking devices controlled in accordance with the condition of said register sections and arranged to block certain elements of said machine during a totaling operation to prevent totaling in certain registers but being ineffective as to other registers, and means controlled by said subtract lever for disabling said locking devices to permit the taking of totals from said blocked register sec- 80

tions after said other register sections have been totaled.

8. In a calculating machine having a register divided into a plurality of sections, each capable of addition and subtraction, depressible keys, differential mechanism controlled by said keys for simultaneously entering amounts in said register sections upon a single cycle of operation of said machine, a single total key, connections therefrom for causing a total to be taken from each of said register sections, negative total locks arranged to prevent operation of said total key when a register section is in negative condition, subtraction control means additional locking devices controlled by elements of said total locks and arranged to block certain elements of said machine during a totaling operation to prevent totaling of said register sections in negative condition, means for releasing said total key to permit totaling in said register sections in positive condition without affecting said additional locking devices, and means controlled by said subtraction control means for preventing blocking by said additional locking devices to enable the taking of true negative totals from said negative register sections upon a subsequent totaling operation after said positive register sections have been totaled.

9. A calculating machine adapted to be given cycles of operation, having an amount determining differential mechanism upon which two dif-

ferent amounts may be indexed at the same time, two registering mechanisms each of which is capable of addition and subtraction whereby either may reach a positive or a negative condition, means for conditioning certain elements of the machine to cause addition or subtraction in said registering mechanisms, means operating during a cycle of operation of the machine to cause two different amounts to be simultaneously entered in their respective registering mechanisms, total taking control means for causing totals to be taken from said registering mechanisms, said total taking control means being controlled by a manipulative means and being operable to cause a true negative total to be taken from either registering mechanism when said registering mechanism is negative, means operating automatically when there is a negative total in one of said registering mechanisms, to lock said manipulative means, means for releasing said manipulative means to enable a total to be taken from the register that is in positive condition, means for preventing taking a total from the registering mechanism that is negative while a positive total is being taken, and means for then releasing said preventing means to enable the total to be taken from the registering mechanism that is in negative condition after the register in positive condition has been cleared.

ROBERT L. MULLER. 30
